FLEXIBLE SHOCKPROOF PROPELLER

John A. Myers, Albany, N. Y., assignor, by direct and mesne assignments, of one-eighth to Mauritz Johnson, and four-eighths to Frederic Streh, both of Albany, N. Y.

Application November 10, 1943, Serial No. 509,763

4 Claims. (Cl. 115—35)

This invention relates to new and useful improvements in propellers for boats and other uses, the principal object being to provide a propeller which will be substantially shock-proof in operation, especially when pressure on the propeller is relieved as when the stern of the boat leaves the water.

Another important object of the invention is to provide a propeller which has a primary ability to yield, thus substantially reducing the shock of starting.

Other objects and advantages of the invention will become apparent to the reader of the following description.

In the drawing—

Figure 1 is a fragmentary side elevational view showing the stern of a ship and certain parts of the present invention in section.

Figure 2 is a fragmentary sectional view taken substantially on the line 2—2 of Figure 1.

Figure 3 is a section taken substantially on the line 3—3 of Figure 1.

Referring to the drawing wherein like numerals designate like parts, it can be seen that the numeral 5 denotes the stern of a ship, while numeral 6 generally refers to the present invention.

Inside of the stern 5 is a stand 7 vertically through which and the back of the stern 5 is disposed a steering shaft 8, the lower end of which connects to the removable top of a box 9 in which is a rotary beveled gear 10 meshing with a pair of bevelled pinions 11, 12.

The bevelled gear 12 has a rearwardly projecting shaft 13 projecting rearwardly of the box 9 and on this shaft 13 is a pair of spaced cups 14, 15, the open sides of the cups being opposed and having their opposed edges beveled as at 16.

The shaft 13 is provided with threads 17. A propeller consisting of a hub 18 is provided with blades 19 and the hub 18 has a beveled side portions 20, 20 which are engageable with either beveled surface 16 of the cups 14, 15.

Numerical 21 denotes a drive shaft which extends through a horizontal slot 22 in the forward side of the gear box 9.

It can now be seen, that the propeller is driven by the shaft 21 and gears 10, 11 and 12 by way of the shaft 13. When the propeller is driven in one direction, it will ride against one of the cups 14, 15 and this interval of movement will relieve the propulsion mechanism of any shock. Further, due to the fact that water is pushed into the corresponding cup 14, or 15 there is a cushioning effect against the propeller as the corre-

sponding beveled portion 20 rides against the beveled portion 16 of the cup. Due to the fact that water will remain in the cups, there will be no likelihood of the propeller having its beveled side sticking or otherwise binding within the beveled portion of the corresponding cup.

Obviously, the entire propeller unit can be oscillated horizontally for the purpose of steering through the medium of the steering shaft 8.

10 While the foregoing specification sets forth the invention in specific terms, it is to be understood that numerous changes in the shape, size and materials may be resorted to without departing from the spirit and scope of the invention as 15 claimed hereinafter.

Having described the invention, what is claimed as new is:

1. A propelling mechanism for boats, comprising a horizontal propeller shaft, friction-clutch 20 cups secured in spaced relation on the propeller shaft, said propeller shaft having a single thread between said friction-clutch cups, and a propeller arranged on the propeller shaft between said friction-clutch cups, said propeller including a 25 hub having threaded engagement with the propeller shaft for movement into engagement with one friction-clutch cup when the propeller shaft is driven in one direction, and into engagement with the other friction-clutch cup when the propeller shaft is driven in the opposite direction, said friction-clutch cups having open sides in opposed relation and including cylindrical walls having beveled end edges at the open sides thereof, said propeller hub being provided with beveled 30 ends engageable with the beveled edges of the respective cups, the friction-clutch cups being of a depth to provide a water cushion therein when engaged by the propeller hub.

2. A propelling and steering device for boats 40 comprising a substantially horizontal drive shaft, a substantially vertical steering shaft, a box fixed to the lower end of said steering shaft and having an arcuate horizontal slot in the front thereof, said drive shaft extending into the box 45 through said slot to permit the box to rotate with the steering shaft relative to the drive shaft, a bevel pinion on the rear end of the drive shaft, a horizontal propeller shaft journaled in the rear of the box and projecting rearwardly therefrom, a second bevel pinion on the front end of the propeller shaft, a bevel gear arranged between and meshing with said pinions and journaled in the box with its axis coincident with the steering shaft, stop members secured in spaced relation on the propeller shaft, said propeller shaft

having a single thread between said stop members, and a propeller arranged on the propeller shaft between said stop members, said propeller including a hub having threaded engagement with the propeller shaft for movement into engagement with one stop member when the propeller shaft is driven in one direction and into engagement with the other stop member when the propeller shaft is driven in the opposite direction.

3. A propelling and steering device for boats comprising a substantially horizontal drive shaft, a substantially vertical rotatable steering shaft, a box having a part fixed to the lower end of said steering shaft, said drive shaft extending into the box, a bevel pinion on the rear end of the drive shaft, a horizontal propeller shaft journaled in the rear of the box and projecting rearwardly therefrom, a second bevel pinion on the front end of the propeller shaft, a bevel gear arranged between and meshing with said pinions and journaled in the box with its axis coincident with the steering shaft, said box embodying

means whereby said part thereof and said propeller shaft may be rotated with the steering shaft relative to said drive shaft, and a propeller arranged on and driven with the propeller shaft.

4. A propelling and steering device for boats comprising a substantially horizontal drive shaft, a substantially vertical rotatable steering shaft, a box fixed to the lower end of said steering shaft and having an arcuate horizontal slot in the front thereof, said drive shaft extending into the box through said slot to permit the box to rotate with the steering shaft relative to the drive shaft, a bevel pinion on the rear end of the drive shaft, a horizontal propeller shaft journaled in the rear of the box and projecting rearwardly therefrom, a second bevel pinion on the front end of the propeller shaft, a bevel gear arranged between and meshing with said pinions and journaled in the box with its axis coincident with the steering shaft, and a propeller arranged on and driven with the propeller shaft.

JOHN A. MYERS.
